UNITED STATES PATENT OFFICE.

JOHN W. HAYWOOD, OF BALDWINSVILLE, NEW YORK.

DUMP-WAGON.

No. 899,011.

Specification of Letters Patent. Patented Sept. 15, 1908.

Application filed November 1, 1907. Serial No. 400,158.

To all whom it may concern:

Be it known that I, JOHN W. HAYWOOD, of Baldwinsville, in the county of Onondaga, in the State of New York, have invented new and useful Improvements in Dump-Wagons, of which the following, taken in connection with the accompanying drawings, is a full, clear, and exact description.

This invention relates to certain improvements in dump wagons in which the box is preferably made hopper shape with an opening in the bottom and provided with a forwardly swinging bottom door adapted to discharge at its rear end, and refers more particularly to the adjustment and manner of controlling the operation of the door.

My main object is to provide a general utility dump wagon which is specifically adapted for road making and similar uses where it is desired to spread the load evenly to any desired depth, during its discharge. In other words I have sought to provide means whereby the operator may easily stop and hold the door in any position in its arc of movement during the discharge of a load so that such load may be spread out evenly over the surface of the ground or may be wholly discharged at once without stopping the wagon.

Another object is to extend the sides of the door upwardly some distance above the bottom at the outer sides of the box so as to retain the load against lateral discharge during the operation of spreading or discharging such load gradually.

A still further object is to hinge the front end of the door to, and some distance above, the bottom of the box so that the arc of movement of the front end of the door will be as high above the ground as possible when the door is swung to its open position.

Another object is to provide the sides of the door and box and also the guard plates which form a part of the door support with a plurality of apertures for receiving the hinge pins and permitting the swinging axis of the door to be shifted nearer to or further from the front side of the bottom of the box.

Other objects and uses relating to the specific parts of the door controlling mechanism will be brought out in the following description.

In the drawings—Figure 1 is a longitudinal vertical sectional view of a dump wagon embodying the various features of my inven-

tion. Fig. 2 is a side elevation partly broken away of the wagon box showing the door as partly open and also showing the adjacent portion of the door controlling cable. Figs. 3 and 4 are transverse sectional views taken respectively on lines 3—3 and 4—4, Fig. 1, except that they show the full width of the box and that one end of the winding drum and its bearing is shown in section. Fig. 5 is a top plan partly in section of one end of the winding drum and its operating mechanism showing also the adjacent portion of the box.

In carrying out the objects stated, I provide a hopper shaped box having substantially vertical parallel sides —1—, front and rear downwardly inclined ends —2— and —3— and a rearwardly inclined bottom door —4—.

The main body of the box is made of wood and is provided with an interior lining of sheet metal and the rear end —3— extends downwardly some distance below the lower plane of the front edge —2— while the lower edges of the sides —1— are disposed in a plane coincident with the lower edges of the front and rear ends, which latter are spaced apart some distance leaving an opening —5— in the bottom of ample size for the discharge of the material.

The bottom door —4— is preferably made of sheet metal of sufficient size to completely close the opening —5— and is provided with opposite upturned integral flanges or sides —6— extending some distance above the bottom and in close proximity to the outer sides of the box, the front ends of said sides —6— being wider than their rear ends and are hinged to the sides of the box by suitable pivotal pins or bolts —7— and also to the inner sides of suitable sheet metal hangers or brackets —8— which are secured to the outer sides of the box. These sheet metal hangers or brackets —8— and also the upper front end of the sides —6— of the door are formed with a series of apertures spaced apart one above the other to receive the pivotal bolts —7— and permit the latter to be adjusted nearer to or further from the bottom of the door so as to raise or lower the arc of movement of the front end of the door to bring the latter nearer to or further from the ground as may be desired and also to vary the speed of opening of said door.

The front and rear ends of the bottom of the door are reinforced by suitable cross bars

—9— and —10— of wood or other suitable material, the rear cross bar being in close proximity to the rear edge of the door and provided with a series of end and intermediate guides or loops —11— and —12— for receiving a cable —13— by which the action of the door is controlled. In the present instance I employ a single cable having its intermediate portion passed under the rear edge of the bottom of the door and upwardly over suitable idlers —14— and then forwardly at opposite sides of the box where their ends are attached to suitable winding drums —15—. These winding drums are secured to a tubular shaft —17— which is journaled in metal bearings —18— in the sides of the box, said shaft being provided near one end preferably just inside of the right hand side of the box with a worm gear —16— meshing with an upright worm 19—, the latter being journaled in a swinging bracket —20— and is provided with an upwardly extending shaft —21— having a handle —22— by which it may be rotated to transmit similar rotary motion to the tubular shaft —17— and drums —15—.

The swinging frame or yoke —20— is pivoted at its lower end at —23— to the adjacent side of the box and preferably consists of a U-shape metal bar having its opposite ends mounted upon the pivotal bolt —23— and its upper portion disposed in a horizontal position forming a bearing for the shaft —21— although the lower end of said shaft is stepped in a cross bar —24— forming a part of and secured to the bracket —20—. This bracket may be rocked forwardly from the shaft —17— to throw the worm —19— out of mesh with the gear —16— when it is desired to discharge the full load at once.

The bracket —20— is held in operative position by a detent —28— which is pivoted at —29— to the adjacent side of the box —1— and is provided with a handle or pedal —30— by which it may be thrown out of engagement against the action of a retracting spring —31— although this spring serves to hold the detent in operative position to hold the worm —19— in mesh with the gear —16—.

The particular object in using the worm gear as means for winding the door operating cable is that it is self-locking and enables the operator to control the opening action of the door under load in which case the detent —28— and worm —19— are left in operative position and the worm is simply rotated in the direction necessary to unwind the cable, thereby allowing the rear end of the door to open as much as may be desired to discharge the load by slow degrees thereby spreading it out to the desired depth over the ground.

The cable —13— is free to render through the guide loops or eyes —11— and —12—

should one side of the door sag or lag behind the other in closing and affords a means for closing both sides of the doors tightly although the transverse movement of the chain under the doors is comparatively slight under all conditions.

The idlers —14— are journaled in brackets —14'— which are secured to the outer sides of the box and in order to prevent undue slackening of the portion of the chain between the idlers and drum, I provide additional guides —13'— also secured to the outer sides of the box substantially midway between the idler —14— and drum shaft —17—.

The cable winding mechanism is mounted upon forward extensions —1'— of the sides of the box some distance in front of the front end —2—, and the drums —15— are located just at the outside of these extensions so that the cables extend from the drums rearwardly along the outside of the box through the guides —13'— and —14'— and over the idler —14— and thence downwardly through the eyes 11— and —12— just underneath the rear end of the bottom of the door so that practically the entire strain of the load upon the door is borne by the chain but any sag or depression of the door may be readily taken up by rotating the worm —19— in the proper direction to further wind the cable —13—.

When the doors are closed in the manner just described they are held in this position by the intermeshing teeth of the worm and gear and if it is desired to discharge the entire load at once, it is simply necessary to disengage the detent —28— from the swinging bracket —20— and to rock said bracket together with the worm —19— and shaft —21— thereon forwardly to throw the worm out of engagement with the gear whereby the drums are free to rotate under the tension of the cables produced by the weight of the load on the door, such load forcing the door to its extreme open position. On the other hand if it is desired to distribute the load evenly over the surface of the ground, the worm is left in mesh with the gear and the detent remains in holding engagement with the bracket whereupon the worm may be rotated by the operator through the medium of the hand piece —22— and shaft —21— to permit the cable to be unwound gradually until said door is opened to the desired degree when the rotation of the worm is stopped, thereby locking the drum shaft against further rotation and holding the door in its adjusted position through the medium of a cable —13—.

What I claim is:

1. In a dump wagon, a dump box having a longitudinally swinging bottom door, and means for changing the position of its axis.
2. In a dump wagon, a dump box having a

downwardly and forwardly swinging bottom door, and means for changing the position of its swinging axis.

3. In a dump wagon, a dump box having a downwardly and forwardly swinging bottom door provided with upwardly projecting sides extending under the outside of the box some distance above its bottom, supports for the door secured to the sides of the box, said supports and sides of the door being provided with a plurality of apertures, and pivotal bolts passed through aligned apertures at the opposite sides of the box, said bolts being adapted to be placed in either of the apertures to change the position of the swinging axis of the doors.

4. In a dump wagon, a dump box having a downwardly and forwardly swinging bottom door, and adjustable pivots for said door.

20 5. In a dump wagon, a dump box having substantially parallel sides and downwardly converging front and rear ends, the rear end extending downwardly a greater distance than the front end, a downwardly and forwardly swinging bottom door having upwardly extending sides hinged to the sides of the box, the hinge-bearing being adjustable to change the swinging axis of said door, and

means for controlling the operation of the door.

6. In a dump wagon, the combination of a dump box having a longitudinally swinging bottom door, a cable controlling the action of said door, a drum for winding the cable, a worm gear on the drum, a worm movable into and out of mesh with the gear, a swinging supporting frame for said worm, means for rotating the worm, and a detent movable into and out of holding engagement with said frame.

7. In a dump wagon, a dump box having a longitudinal swinging bottom door, means for controlling the action of said door including a worm and gear, one of the latter parts being movable into and out of engagement with the other part, means for rotating the worm, a swinging supporting frame for said movable part and a detent movable into and out of engagement with said swinging frame.

In witness whereof I have hereunto set my hand this 21st day of October 1907.

JOHN W. HAYWOOD.
